UNITED STATES PATENT OFFICE.

GEORGE W. BULLEY, OF CHICAGO, ILLINOIS.

DESIGN FOR A VEHICLE-BODY.

45,686.

Specification for Design.

Patented Apr. 28, 1914.

Application filed December 22, 1913. Serial No. 808,290. Term of patent 14 years.

To all whom it may concern:

Be it known that I, GEORGE W. BULLEY, a citizen of the United States, residing at Chicago, in the county of Cook and State of Illinois, have invented a new, original, and ornamental Design for a Vehicle-Body, of which the following is a specification, reference being had to the accompanying drawing, forming a part thereof, and wherein—

Figure 1 is a side elevation of the vehi-

cle body illustrating my new design, and Fig. 2 is a perspective view thereof.

I claim:

The ornamental design for a vehicle body as shown.

Chicago, Illinois.

GEORGE W. BULLEY.

Witnesses:

CHARLES H. SEEM,

HAROLD G. ROCKWELL.
